DESIGN FOR LOOP DETECTOR CONTROL UNIT

Bjarne Netland, Liverpool, N.Y., assignor to Crouse-Hinds Company, Syracuse, N.Y., a corporation of New York

Filed Sept. 30, 1965, Ser. No. 87,235

Term of patent 7 years

(Cl. D26—1)

FIGURE 1 is a front elevational view of a loop detector control unit showing my new design.

FIGURE 2 is a top plan view of the control unit shown in FIGURE 1.

FIGURE 3 is a side elevational view of the control unit shown in FIGURE 1.

FIGURE 4 is a sectional view taken on line 4—4, FIGURE 1.

FIGURE 5 is a sectional view taken on line 5—5, FIGURE 1.

The side opposite that shown in FIG. 3 is a mirror image thereof, while the back of the control unit is plain and unornamented.

I claim:

The ornamental design for loop detector control unit, as shown and described.
